MOUNTING MEANS FOR CIRCUIT BREAKERS OR THE LIKE

Original Filed Nov. 20, 1943

UNITED STATES PATENT OFFICE

2,547,156

MOUNTING MEANS FOR CIRCUIT
BREAKERS OR THE LIKE

Fred Farrell, Cedar Rapids, Iowa, assignor to
Electrical Engineers Equipment Company, Mel-
rose Park, Ill., a corporation of Illinois

Original application November 20, 1943, Serial
No. 511,019. Divided and this application No-
vember 19, 1945, Serial No. 629,423

3 Claims. (Cl. 200--168)

1

The present invention relates to an improvement in mounting means for a circuit breaker and more particularly to a circuit breaker of the automatic opening and reclosing type.

The present application is a division of my earlier application Serial No. 511,019, filed November 20, 1943, now Patent No. 2,506,546, May 2, 1950, for Circuit Breaker.

A switch or circuit breaker of the above type should be readily and safely removable from service or be replaced in service without deenergizing the line and without subjecting the operator to the hazard of too close proximity to a dangerous electric circuit, so that the switch contacts and associated controlling mechanism requiring repair or adjustment, due to wear on the various parts and stresses occasioned by service may be readily attended to by a repairman. It is an object of my invention to provide a mounting means primarily for use with an automatic reclosing switch having suitably associated insulators comprising the stationary part or section of the switch for incorporation in the line, and a removable housing section comprising the switch contacts and associated controlling mechanism in which the size and weight of the removable housing section are sufficiently small to be within the physical scope of an operator or repairman to manually remove or replace by the use of an insulated hook stick or pole.

Further objects, advantages and features of my invention will appear from the detail description.

Now, in order to acquaint those skilled in the art with the manner of constructing and utilizing mounting means in accordance with my invention, I shall describe in conjunction with the accompanying drawings a preferred embodiment of the same.

Figure 1 is a mounting means for a side elevational view of a circuit breaker constructed in accordance with my invention; and

Figure 2 is a plan view of the mounting means and circuit breaker of Figure 1.

The mounting means of my invention comprises in general a stationary mounting frame, insulated for supporting a removable housing section, electrical terminals for the line wires and for engaging the contacts of the removable housing section, and electrical conducting links for bypassing the removable housing section. The mounting frame as shown in the drawing comprises a channel member 254 to which is rigidly fixed frame member 255 assembled in

2

T formation, as shown. Bolts 256 and 257 are assembled in slotted holes formed in the member 255, and together with a clamping member 253 to provide for mounting of the same on wooden cross bars or other structure. Insulators 259 and 260 are fixed to opposite ends of the member 254 and extend at substantially right angles to the plane of the mounting frame with a center to center spacing coinciding with center to center spacing of the insulating housings 9 and 10 of the removable section or housing portion of the switch shown in the drawing. The insulated housings 9 and 10 enclose suitable switch members, for example, as described in my above identified application. Supporting brackets 262 and 263 are assembled on the other ends of insulators 259 and 260, respectively, and electrical terminal members 264 and 265 are assembled to the brackets 262 and 263 respectively by the terminal bolts 266 and 267. The terminal bolts 266 and 267 are also utilized for forming terminals for the line wires.

The lower ends of the terminal elements 264 and 265 are of substantially V form to engage in the openings 278 and 279 of switch contacts 7 and 8 in the insulated housings 9 and 10, respectively, and also act as a supporting means for the removable housing section of the circuit breaker shown. In addition they form electrical contacts with the lips 280 with which the contacts 7 and 8 are formed.

The insulator 251 at the lower end of the mounting frame 255 has an angle bracket member 275 of a clamping means 281 rigidly assembled at its outer end. A stud 276 is threadedly engaged in the member 275. A slotted bracket member 277 forming another element of the clamping means is fixed to the base 249 of the removable housing section, and is so located in relation to the bracket member 275 and the stud 276, that when the removable housing section has been assembled with the stationary section with the fixed contacts 7 and 8 engaged over the curved ends of terminal elements 264 and 265, the stud 276 will engage in the slot of bracket 277, and the removable housing section will be held rigidly in place by tightening the stud 276. The lower end of stud 276 is of square cross section for snugly fitting into a conformably shaped recess in the end of an insulated hook stick or the like for manipulation by an operator.

A conducting link 268 is hinged at 269 in electrical contact with the upper end of the terminal element 264 and a stud 272 is carried at

the opposite end thereof. A conducting link 271 is hinged at 270 in electrical contact with the upper end of the terminal element 265. The relative lengths of links 268 and 271 are such that they may be moved into contacting position with each other with stud 272 of link 268 disposed in slot 273 formed in the outer end of link 271. Rigid electrical contact is maintained therebetween by tightening of stud 272. The end of stud 272 is formed like stud 276 for engagement with the recessed end of the aforementioned insulated hook stick or the like to provide for safe manipulation by the operator. A stop lug 274 is formed on terminal 264 in position so that when the link 268 is moved into engagement therewith, the free end of the link 268 is then in position for the slot 273 of link 271 to engage the shank of stud 272 carried by link 268. It is therefore possible for an operator to close the line circuit through links 268 and 271 and thereby allow opening, closing, removal, or replacement of the removable housing section enclosing a circuit breaker or the like without interrupting the line current.

In the preferred form of my invention a prong member 258 is fixed to the base plate 249 to extend downwardly, and it has an outer end portion of square cross section, like studs 272 and 276, for snug fitting engagement with the recessed end of the previously mentioned insulated hook stick. Other stud members, such as shown at 119 and 163 for certain of the instrumentalities of the circuit breaker enclosed within the removable housing section, and the outer end of a worm gear shaft 13 for a spring motor for the breaker, are also preferably provided with outer end portions of the same size and configuration as outer end portions of studs 272 and 276, and prong member 258, so that all of them may be engaged with a common hook stick.

In view of the construction described, the removable housing section is adapted to be supported on a hook stick by disposing the prong member 258 in the recessed end of the hook stick. The hook stick may then be suitably manipulated to mount and dismount the removable housing section.

While I have shown what I consider to be a preferred embodiment of my invention it will be understood that various details, rearrangements, and modifications may be made therein without departing from the spirit and scope of the invention.

I claim:

1. A mounting means for an automatic circuit breaking switch or the like having a pair of spaced switch contacts, comprising a mounting frame for supporting the switch, and means providing a three-point mounting of the switch upon said frame comprising, a pair of terminals carried by said frame and spaced correspondingly to the spacing of said switch contacts, said switch contacts and said terminals being formed to provide a two-point suspension mounting of the switch upon said mounting frame, clamping means between the mounting frame and the switch providing the third mounting point for the latter, and a pair of blade members each pivotally

mounted at one end thereof to one each of said terminals, said blades being adapted to be positioned to engage the other ends thereof with each other to shunt said switch.

5 2. Mounting means for a switch or the like having a pair of spaced switch contacts comprising, a mounting frame for supporting the switch, means providing a three point mounting of the switch upon the mounting frame comprising, a 10 pair of terminals carried by said mounting frame and spaced correspondingly to the spacing of said switch contacts, said contacts and said terminals being formed to provide a two point suspension mounting of said switch upon said mounting frame, clamping means providing the third 15 mounting point comprising a bracket member carried by said mounting frame, and a bracket member adapted to be carried by said switch, a bolt having its outer end formed to be engaged by a hook stick or the like for drawing said bracket members together to provide pressure contact between said terminals and said switch contacts, and a projection on said switch adapted to be engaged by a hook stick or the like for manually positioning said switch upon said mounting frame.

20 3. Mounting means for a switch or the like having a pair of spaced contacts comprising, a mounting frame for supporting said switch, means providing a three point mounting of said switch upon said mounting frame comprising, a 25 pair of terminals carried by said mounting frame and spaced correspondingly to the spacing of said switch contacts, said contacts and said terminals being formed to provide a two point suspension 30 mounting of said switch upon said mounting frame, clamping means providing the third mounting point comprising, a bracket carried by said mounting frame, and a bracket member carried by said switch, a bolt for securing said bracket members together providing pressure contact between said terminals and said switch contacts, a projection on said switch by which it is 35 positionable upon said mounting frame, and a pair of blade members pivotally mounted at one end of each thereof to one of each of said terminals, a bolt carried by the other end of one of said blade members for securing the opposite ends of said blade members to each other, and the outer ends of said bolt and projection being formed to be engaged by a hook stick or the like.

FRED FARRELL.
